UNITED STATES PATENT OFFICE

2,001,513

CIRCUIT BREAKER

Ernest Zurcher, Schenectady, N. Y., assignor to
General Electric Company, a corporation of
New York

Application June 27, 1933, Serial No. 677,795

14 Claims. (Cl. 200—124)

My invention relates to circuit breakers, more particularly to circuit breakers of the type provided with arc chutes or housings, and has for an object the provision of a simple, inexpensive and reliable circuit breaker.

While not limited thereto, my invention is particularly applicable to thermally operated switches for the control of electric motors. Heretofore, the arc chutes have been either hingedly connected to the switch base or they have been arranged so that they can be removed as a unit independently of the switch contacts to permit ready inspection of the contacts. In case the contacts have worn considerably and replacement is to be made it has been necessary to remove the arc chute. Due to carelessness the switch has sometimes been reassembled without placing the arc chute in its proper place and the electric arcs due to the breaking of a heavy current have caused considerable damage to the switch mechanism and have endangered the operator's safety.

In carrying out my invention in one form thereof, I provide an arc chute or arc housing which serves not only to enclose the contacts but also as a support for the movable contacts. Consequently, the switch cannot be operated unless the arc chute is in position because the operating mechanism is connected to it. More specifically, the arc chute or housing is pivotally mounted at one side of the stationary contact and the operating mechanism engages the arc chute on the other side of the stationary contact. In multiple circuit breakers the arc chute is provided with separate compartments for the respective switch contacts, the walls of the separate compartments cooperating with the base of the switch to enclose at all times the switch contacts forming each pole of the switch. Consequently, a flame-proof structure is provided because the arcs occurring at the contacts are isolated from each other and cannot come into contact with the operating mechanism. An overload device is similarly enclosed to prevent injury to the mechanism in case of extremely high overload current.

For a more complete understanding of my invention, reference should be had to the drawings wherein I have shown in Fig. 1 a sectional elevation of a switch embodying my invention; Figs. 2 and 3 are fractional sectional elevations showing the operating mechanism of Fig. 1 in different positions; Fig. 4 is a plan view of the switch shown in Fig. 1 with certain parts omitted to show the construction more clearly; Fig. 5 is an elevation of the thermal overload device shown

in Fig. 9; Fig. 6 is a plan view of Fig. 5; Fig. 7 is a sectional elevation of a portion of the heating coil; Fig. 8 is a plan view of Fig. 7; Fig. 9 is a perspective view of the thermal device; Fig. 10 is a perspective view of the heating element and casing for the thermal device; Fig. 11 is a detailed view of the tripping member; Fig. 12 is a plan view looking into the interior of the arc chute; Fig. 13 is a sectional elevation taken on the lines 13—13 of Fig. 4, while Fig. 14 is a perspective view of a modified form of arc chute embodying the invention.

Referring to the drawings, I have shown my invention in one form as applied to a triple pole switch provided with a base 10 formed of insulating material. The movable contacts 11, 12, and 13 and the stationary contacts 15, 16 and 17, Figs. 1 and 13, are identical in construction. Consequently, only one pole of the switch will be described in detail. As shown, the stationary contacts 16, preferably formed of silver, are secured to the conductors 19 and 20 which are fastened to the base by means of screws 21 and 22. The movable contacts 12, Fig. 12, are supported by a bridging member 28 provided with a rectangular opening 28 at its center to receive a rectangular post 31 fastened to the arc housing 32 by means of a screw 33. A screw 34 and a washer 35 serve to maintain the bridging member on the post against the bias of a compression spring 36, the bridging member being thus slidably mounted on the post.

Referring to Figs. 1 and 13, it will be observed that the stationary contacts 16 are mounted upon a ledge or projection 40 formed integrally with the base. Similarly, the stationary contacts 15 and 17 are mounted upon projections or ledges 41 and 42. The arc chute or housing 32 formed of insulating material, besides serving to support the movable contacts 11, 12 and 13 is provided with side walls 44, 45, 46 and 47 for cooperation with the channels or grooves between projections 40 to 42, inclusive, to enclose completely the respective stationary and movable contacts in separate chambers. That is to say, each of the walls 44 to 47, inclusive, extends below the upper surfaces of the respective projections 40 to 42, inclusive, when the switch is in either the open or closed position.

The movable contact members, secured to the arc housing 32, are simultaneously operated to open and closed circuit positions with a snap action by means of the operating mechanism 50, Figs. 1-4 inc. The operating mechanism is arranged to rotate the arc housing 32 about a pivot

formed by a pair of members 52 and 53 secured to the arc housing by the screws 54 and 55, the member 52 being provided with a pivot pin 56 which extends into a notch 57 provided in the base 10. Similarly, the supporting member 53 is provided with a pivot pin 58 extending into a notch 59. In order to facilitate the assembly of the switch the two supporting members 52 and 53 are connected together by an insulating strip 60.

The operating mechanism 50, of any suitable form, is preferably connected to the arc housing 32 by means of a rod 70 extending into the notches 71 and 71a provided in the arc housing. The rod 15 70 is carried at one end of a link 72 which is pivotally mounted on a pivot pin 73 secured to the frame or base 74 of the operating mechanism. In order to impart a snap action to the movable contacts, movement is imparted to the link 72 by 20 a toggle mechanism comprising the links 75 and 76 arranged to be operated to the made and broken positions by means of an over-center spring 78. It will be observed that the over-center spring is connected at one end to a pivot pin 79 supporting the links 75 and 76, and at its other end to a pin 80 carried by an operating handle 81 provided with a pair of spaced arms secured by a pivot pin 82 to the frame 74. By rotating the operating handle 81 in a clockwise direction 25 from the position shown in Fig. 1 to the position shown in Fig. 2, it will be observed that the spring 80 passes through its dead-center position to apply its bias to the toggle mechanism to operate the links 75 and 76 to the made position. Consequently, the link 72 is operated in a clockwise direction to close quickly the contacts of the switch and of course as soon as the operating handle 81 is returned to the position shown in 30 Fig. 1 the contacts are quickly operated to their open circuit position.

As shown, the operating mechanism 50 includes a current responsive tripping means so that the switch contacts are operated to their open circuit position whenever a predetermined current flows 45 through the switch contacts. The automatic tripping of the circuit breaker is accomplished by the provision of a supporting member or cradle 90, provided with spaced arms disposed on opposite sides of the link 72 but within the legs of the handle 81, pivotally mounted on a pin 91. The supporting member 90 has an upturned projection 93 arranged to nest within a notch 94 provided in one end of the link 76. When the switch contacts are in the closed position as shown in Fig. 2, it will be observed that the spring 78 is exerting a 50 force on the toggle mechanism, a component of which is effective to rotate the supporting member 90 in a clockwise direction about its pivot 91. If this motion is permitted, it will be observed that the notch 94 provided in one end of the toggle mechanism will be rotated beyond the dead-center position, thereby breaking the toggle and causing the switch to be quickly operated to its open circuit position. However, the supporting member 90 is normally maintained in the position 55 shown in Fig. 1 by means of a thermal tripping member 100, Fig. 11, which is secured by a pin 102 to the lower end 103 of the support 90. The tripping member 100 has two outwardly extending 60 latching members 105 and 106 pivotally secured to it by means of a washer 108 and a cotter pin 109 cooperating with the upwardly extending projection 110. These latching members 105 and 106 are normally biased away from each other by 65 means of a compression spring 111 and into en-

gagement with a pair of gear wheels 115 and 116, Fig. 4, provided on the thermal overload devices 119 and 120. Since the thermal devices 119 and 120 are identical in construction only one of them, the device 120 will be described in detail. As 5 shown in Figs. 9 and 10, the gear wheel 116 is carried by a sleeve 130 nesting within a metal cylinder 131. The sleeve 130 is normally soldered to the cylinder 131 and thereby holds the gear 116 from rotating in accordance with the bias 10 exerted upon it by the tripping member 100. Similarly, the gear 115 is maintained stationary by means of a solder film between its sleeve and cylinder.

As shown in Figs. 8 and 10, the thermal over- 15 load device 120 is provided with a heating coil 135 mounted within an insulating casing 136 by means of the terminal members 138 and 139. The metal cylinder 131 is supported by a base 140 formed of insulating material and is removable as a unit from the switch base 10. For example, the base 140 of the thermal device is provided with terminal screws 150 and 151 which serve to support conductors 152 and 153, each of which is provided with extensions for completing 20 electrical connections from the conductor 155 to the conductor 156. Similarly, the thermal responsive device 119 is constructed so that it can be removed as a unit from the switch.

Since the thermal devices are constructed as 30 units the switch can be calibrated for different applications by simply assembling the proper thermal device on the circuit breaker for a particular application. Or, if the switch has been assembled with 25 ampere thermal devices it is 35 only necessary to loosen the nuts 160 and 161 and either new heating coils can be assembled on the thermal overload device or by loosening the nuts 163 and 164 new thermal devices can be substituted for the ones already in the switch. 40

In order to provide a flame-proof construction, it will be observed that the casing 136 is provided with extensions 170 and 171 arranged to be received in complementary relation with notches 172 and 173 provided in the base 140, the inner 45 walls 172a and 173a of the notches being covered by the extensions. Besides serving to enclose the heating coil, the extensions 170 and 171 protect the heater coil from mechanical injury. For example, if the casing is dropped the extensions will protect the coil from injury. 50

It will be understood that the switch can be operated in response to overload in any one of the phases since the thermal devices 119 and 120 are arranged to be connected respectively on the 55 outside legs of a three phase circuit.

In the operation of my switch in response to overload current it will be assumed that the parts are in the positions shown in Figs. 2 and 13 and that an overload current is flowing through the 60 heater coil 135 of the thermal responsive device 120. As soon as the heating coil 135 has produced a sufficient degree of heat, the solder securing the sleeve 130 to the housing 131 is melted and the gear wheel 116 is released for rotation in accordance with the bias applied to it by the latching member 105, tripping member 100, supporting member 90 and the over-center spring 78. Consequently to the rotation of the gear wheel 116 the latching member 105 moves in a direction to rotate the supporting member 90 in a clockwise direction about its pivot 91. At the same time the tripping member 100 rotated about the pivot pin 102 operates to release the latching member 106 70 from the gear 115. As soon as the upward projec- 75

tion 93 of the supporting member rotates the notched end 94 of the toggle mechanism over the dead-center position (Fig. 2), the over-center spring 78 breaks the toggle causing the rotation of 5 the link 72 about its pivot 73 to operate with a snap action the arc chute 32 to the open circuit position. At the same time the handle 81 is operated to a mid-position.

In order to reset the thermal responsive devices the latching members 105 and 106 are returned to a position to engage the gears 115 and 116 by means of extensions 182 formed integrally with the operating handle 81. The extensions 182 shown in section in Fig. 11 engage 10 the pin 102 and act to move bodily the tripping member 100 and the latching members 105 and 106 to their normal latched-in positions when the operating handle is operated from its mid-position to the off position. Since the switch 15 is reset by the operation of the handle from the mid-position to the off position, it will be observed that the circuit breaker is trip free. That is to say, the operating handle 81 even though operated cannot maintain the switch in the 20 closed circuit position if a current exists of sufficient magnitude to release either of the gears 115 or 116 because the tripping member 100 must be in its normal position before the switch can be closed and because the tripping 25 of the switch occurs independently of the handle.

In case it is desired to inspect the contacts after a large number of operations, it is only necessary to remove the screws 54 and 55. The 30 supporting members 52 and 53 can be rotated so that the pins 56 and 58 are removed from their notches 57 and 59. The arc chute can then be rotated about the pivot pin 70 until it is freed from the molded base. In case the movable contacts need to be replaced it is only necessary to remove the screws, for example, the screw 35 securing the bridging member 25 of the movable contacts 12 to the rectangular post 31. Similarly, the stationary contacts can be replaced by removing the screws, for example, the 40 screws 21 and 22 securing them to the base 10.

The arc chute or housing 32 can be constructed in two or more parts if desired. For example, I have shown in Fig. 14 a base portion 45 190 and a cover portion 191 arranged to support the movable contacts. In this form of my invention the contacts can be inspected by simply removing a pair of screws (not shown) arranged to extend through the holes 192 and 193 50 provided in the cover 191 and into the screw threads 194 and 195 provided in the base portion 190.

It will be observed that L-shaped members 197-199 are provided instead of washers to hold 55 the contacts on their respective supporting members. The bent-over portion 199a serves to vary the position of the bridging member. Consequently, the circuit breaker can be assembled so that either the upper or lower contacts of each 60 bridging member will first interrupt the circuit.

While I have shown a particular embodiment of my invention, it will be understood, of course, that I do not wish to be limited thereto since many modifications may be made, and I, therefore, contemplate by the appended claims to 65 cover any such modifications as fall within the true spirit and scope of my invention.

What I claim as new and desire to secure by Letters Patent of the United States, is:

1. A circuit controlling device comprising a

base member formed of insulating material and provided with a ledge, a switch contact mounted on said ledge, an arc housing formed of insulating material and provided with walls forming a flame-proof chamber, a second contact mounted within said chamber, means mounting said housing and said base for predetermined relative movement to operate one of said contacts with respect to the other between open and closed circuit positions, said walls of said housing overlapping said ledge an amount sufficient to provide a flame-proof chamber for both of said contacts when said housing is in either said open or said closed circuit position. 5

2. A circuit controlling device comprising a base 15 member formed of insulating material and provided with a ledge, a stationary switch contact mounted on said ledge, an arc housing formed of insulating material and provided with walls extending into overlapping relationship with 20 said ledge to enclose said stationary contact, a movable contact secured to said arc housing between said walls for cooperation with said stationary contact to open and close a circuit, operating means connected to said housing for operating said housing and said movable contact between open and closed circuit positions, said walls of said housing overlapping said ledge a 25 predetermined amount when in said open circuit position and a greater amount when in said 30 closed circuit position.

3. A circuit controlling device comprising a plurality of pairs of spaced apart fixed contacts mounted in alignment, an arc housing formed of insulating material and provided with separate 35 compartments surrounding at all times each pair of said contacts, mounting means providing for relative movement of said housing with respect to said fixed contacts, operating means including a handle, means operable in response to movement of said handle for moving said arc housing between predetermined positions, and a bridging contact mounted in each compartment of said arc housing for movement therewith into and out of bridging circuit controlling engagement 40 with the corresponding pair of fixed contacts, said housing being formed so that each of said compartments surrounds its bridging contact and its cooperating stationary contacts when said housing is moved to either of said positions. 50

4. A circuit controlling device comprising walls of insulating material forming a flame-proof arcing chamber, a movable contact mounted on one of said walls of said chamber, means mounting said chamber for a predetermined movement 55 between open and closed circuit positions, a stationary contact, a projection for supporting said stationary contact within said chamber, said walls of said chamber being formed to overlap said projection when said chamber is in either 60 said open or said closed circuit position.

5. A circuit controlling device comprising a base member formed of insulating material, a stationary contact mounted on said base member, an arc housing formed of insulating material and provided with walls surrounding said member, means for detachably mounting said arc housing for movement with respect to said fixed contacts, said housing being provided with a slot, operating means having an element slidably engaging said slot to effect movement of said housing between open and closed circuit positions, a switch contact nesting within an adjacent pair of said walls and operable by said housing into and out of engagement with said stationary contact. 75

tact, said walls of said housing surrounding said base member when said housing is in either said open or said closed circuit position.

6. A circuit controlling device comprising a fixed contact, an arc housing for surrounding said contact and provided with a pivotal bearing on one side of the contact and a slot on the opposite side of the contact, means cooperating with said pivotal bearing for mounting the arc housing for movement with respect to the fixed contact, operating means having an element adapted to engage with said slot to effect movement of the arc housing, and a second contact mounted in the arc chute for movement therewith into and out of circuit controlling engagement with said fixed contact.

7. A circuit controlling device comprising a base member formed of insulating material, a stationary contact mounted on said base member, an arc housing formed of insulating material and provided with walls surrounding said member, operating means connected to said housing for operating said housing between open and closed circuit positions, a switch contact nesting within an adjacent pair of said walls and operable by said housing into and out of engagement with said stationary contact, said walls of said housing surrounding said member when said housing is in either said open or said closed circuit position.

8. A circuit controlling device comprising a pair of spaced apart fixed contacts, an arc housing provided with walls surrounding said pair of fixed contacts and provided with a support extending between said fixed contacts from the opposite wall of said arc housing, means located at one side of said contacts for detachably supporting said arc chute for pivotal movement with respect to said fixed contacts, operating means detachably engaging said arc chute on the opposite side of said contacts and a bridging contact detachably mounted on said support for movement with the arc housing into and out of circuit controlling engagement with said spaced apart fixed contacts.

9. A circuit controlling device comprising a base member formed of insulating material and provided with ledges spaced apart one from the other, a switch contact on each of said ledges, an arc housing formed of insulating material and provided with walls at all times extending between said ledges and overlapping said ledges, and a switch contact secured to said arc housing between each pair of adjacent walls for movement with said arc housing into and out of engagement with said first mentioned contact, said walls and said ledges overlapping one another to form flame-proof arcing chambers when said contacts are either in or out of engagement.

10. A circuit controlling device comprising a base member formed of insulating material and provided with ledges laterally spaced apart one from the other, a pair of fixed contacts spaced apart from each other and fastened to each of said ledges, an arc housing formed of insulating material and provided with partitions extending between said ledges and with side walls overlapping said ledges on all four sides thereof to provide flame-proof chambers for each pair of said contacts, a bridging contact mounted on said arc housing between said partitions and said side walls for movement therewith into and out of bridging circuit controlling positions with said fixed contacts, and means for operating said arc housing between said positions.

11. A circuit controlling device comprising a base member formed of insulating material and provided with ledges laterally spaced apart one from the other, a pair of fixed contacts spaced apart from each other and fastened to each of said ledges, an arc housing formed of insulating material and provided with partitions extending between said ledges and with side walls overlapping said ledges on all four sides thereof to provide flame-proof chambers for each pair of said contacts, a bridging contact mounted on said arc housing between said partitions and said side walls for movement therewith into and out of bridging circuit controlling positions with said fixed contacts, and operating means for manually operating said arc housing between said positions and provided with an overload release for operating said contacts out of said bridging circuit controlling position, said overload release comprising a solder film latch, a heating coil connected in circuit with said contacts, and an enclosing casing for removably supporting said coil with respect to said latch.

12. A circuit controlling device comprising a base member formed of insulating material and provided with ledges laterally spaced apart one from the other, a pair of fixed contacts spaced apart from each other and fastened to each of said ledges, an arc housing formed of insulating material and provided with partitions extending between said ledges and with side walls overlapping said ledges on all four sides thereof to provide flame-proof chambers for each pair of said contacts, a bridging contact mounted on said arc housing between said partitions and said side walls for movement therewith into and out of bridging circuit controlling positions with said fixed contacts, operating means for operating said arc housing between said positions, and a thermal overload device for said operating means comprising a solder film latch, an insulating support for said latch, fastening means for securing said support to said base member, said support being provided with notches on its opposite walls, a heater coil for said latch, an enclosing casing for said coil provided with projections for protecting said coil from injury and for cooperation with said notches thereby to enclose said heating coil.

13. The combination with a circuit controlling device provided with contacts operable between open and closed circuit positions, of a thermal overload device for operating said contacts from a closed circuit position to an open circuit position comprising a solder film latch, a support formed of insulating material for said latch and provided with notches on opposite sides of said latch, a heating coil for said latch and an enclosing casing for said coil provided with extensions arranged to fit into said notches.

14. An overload device comprising a support of insulating material, a member rigidly secured to said support, a second member normally fastened to said first member by a solder film, a heater coil for said members, said support being provided with notches on the outer portion thereof, and an enclosing casing for supporting said coil and provided with extensions arranged to fit into said notches so as to form in cooperation with said base a flame-proof chamber for said coil.

ERNEST ZURCHER.
